UNITED STATES PATENT OFFICE.

CHARLES RUBEN, OF PITTSBURGH, PENNSYLVANIA.

MAN'S NECKWEAR.

Application filed March 24, 1924. Serial No. 701 315.

To all whom it may concern:

Be it known that I, CHARLES RUBEN, a citizen of the United States, residing at Pittsburgh, in the county of Allegheny and 5 State of Pennsylvania, have invented certain new and useful Improvements in Men's Neckwear, of which the following is a specification.

This invention relates to men's neckwear, 10 and consists of an improvement in bow neckties having for its object the production of ready made bow ties resembling a bow tied by the wearer.

In the drawing forming a portion of this 15 specification and wherein like numerals of reference designate corresponding parts throughout the several views:—

Figure 1 is a front elevation of a bow tie in accordance with my invention.

20 Figure 2 is a similar view showing in dotted lines the supporting frame internally supporting the tie fabric.

Figure 3 is a front elevation of the supporting frame.

25 Figure 4 is a top plan view thereof.

Referring in detail to the drawing 1 denotes a bow necktie constructed of any suitable fabric and provided with a supporting frame positioned therein in accordance with 30 this invention.

The supporting frame comprises a cross-bar 2 which is constructed from a narrow flat strip of resilient or spring metal. The cross-bar 2 is formed to provide a horizontally extending edgewise center portion 3, while the end portions 4, of the cross-bar 2, are disposed to extend vertically edgewise. In other words, the center portion 3 of the cross-bar 2 is flatly disposed at right angles 35 with respect to the flat disposition of the end portions 4 thereof.

A vertically disposed cylindrical supporting member 5 is secured to each end, of the cross-bar 2 by coiling the ends of the latter 45 around the central portion of respective members 5, as indicated at 6. The supporting members 5 consist of a roll of stiffened fabric 7 provided with a wadding filler 8, thereby forming yieldable supporting members 50 which are slightly compressed at their centers by the clamping action of the coiled ends of the cross-bar 2, and which taper outwardly from their engaged centers to the ends 10 thereof. The supporting members 55 5, when secured to the cross-bar 2, in the manner described, are disposed forwardly

relatively to the horizontal alignment of the cross-bar 2, for the purpose to be described.

When positioned in the tie 1 my improved supporting frame is embedded between the 60 layers of the fabric constituting the forward wings 11 of the tie. The knot 12 of the bow tie is secured around the central portion 3, of the cross-bar 2. The formation of the central portion 3, as herein stated, provides 65 the shoulders 9 which will prevent the longitudinal movement of the cross-bar 2 when the latter has been secured in position in the tie by the manufacturer.

The supporting members 5 are of a length 70 but slightly less than the width of the wings 11 in which they are mounted and extend adjacent to the ends of the said wings 11. The contour of the members 5 and their arrangement in respective wings 11 together 75 with the disposition of the central portion 3, of the cross-bar 2, impart an ostensible perfunctory fullness to the wings 11 and to the knot 12 thereby adding to the attractiveness of the general conformation and appearance of the tie.

The formation of the resilient cross-bar 2 with the right angularly disposed central portion 3 allows a vertical spring movement to the end portions 4 and to the members 5 85 and wings 11 associated therewith, whereby the attachment of the tie is facilitated and permitting of its adjustment to accommodate itself for use in any manner in connection with any style of collar.

90 What I claim is:

1. A bow necktie including an interior supporting frame consisting of a resilient metal strip cross-bar having its central portion disposed to extend at right angles with 95 respect to the end portions thereof, and a cylindrical member fixed to each end of said cross-bar, substantially as described and for the purpose set forth.

2. A bow necktie including an interior supporting frame consisting of a resilient metal strip cross-bar having its central portion disposed to extend horizontally edgewise and the end portions thereof to extend vertically edgewise, and a cylindrical vertically disposed member fixed to each end of said cross-bar, substantially as described and for the purpose set forth.

3. A bow necktie including an interior supporting frame consisting of a resilient metal strip cross-bar having its central portion disposed to extend at right angles with 110

respect to the end portions thereof, and a cylindrical member fixed to each end of said cross-bar, and positioned forwardly of the latter, substantially as described and for the purpose set forth.

4. A bow necktie including an interior supporting frame consisting of a resilient metal strip cross-bar having its central portion disposed to extend horizontally edgewise and the end portions thereof to extend vertically edgewise, a cylindrical vertically disposed member fixed to each end of said cross-bar and positioned forwardly of the latter, substantially as described and for the purpose set forth.

5. A bow necktie including an interior supporting frame consisting of a resilient metal strip cross-bar having its central portion disposed to extend horizontally edgewise and the end portions thereof to extend vertically edgewise, a cylindrical vertically disposed member fixed to each end of said cross-bar and positioned forwardly of the latter, each of said members consisting of a roll of stiffened fabric provided with a wadding filler, substantially as described and for the purpose set forth.

In testimony whereof I affix my signature.

CHARLES RUBEN.
